UNITED STATES PATENT OFFICE.

BROR J. LINDGREN, OF BUFFALO, NEW YORK, ASSIGNOR TO NIAGARA MACHINE & TOOL WORKS, OF BUFFALO, NEW YORK, A CORPORATION OF NEW YORK.

BARREL-SEAMING MACHINE.

Application filed July 25, 1927. Serial No. 208,080.

This invention relates to a barrel seaming machine and more particularly to a machine of the character which simultaneously connects sheet metal heads with opposite ends 5 of a sheet metal body and which is generally known as a double seamer.

A machine of this type is shown in Letters Patent No. 1,486,974 Mar. 18, 1924, and the present invention relates to improvements therein.

The object of the present invention is to improve the means whereby the chucks are moved one relatively to another for gripping and releasing the barrel; also to improve the 15 means for actuating the tools or rolls for seaming the joints between the body and the heads; also to provide automatic stop mechanism which limits the movement of the chucks one toward and from the other; also 20 to provide automatic stop mechanism for arresting the operation of the seaming mechanism at the end of each cycle of seaming operations, and to improve the machine in various details of construction.

25 In the accompanying drawings:—

Figure 1 is a front elevation of a barrel seaming machine embodying my invention.

Figure 2 is a fragmentary rear elevation of the upper part of the same.

30 Figure 3 is a fragmentary vertical cross section taken on line 3—3 Fig. 2.

Figure 4 is a vertical longitudinal section taken centrally through the machine.

Figure 5 is a fragmentary rear elevation 35 of the lower part of the machine.

Figure 6 is an end elevation of the machine viewed from the left hand end of the same.

Figure 7 is a vertical cross-section taken 40 on line 7—7 Fig. 1, and showing one of the turning or preliminary rolls in its operative position.

Figure 8 is a similar view showing one 45 of the setting down or finishing rolls in its operative position.

Figure 9 is a horizontal section taken on line 9—9 Fig. 1.

Figure 10 is a fragmentary vertical longitudinal section taken on line 10—10 Fig. 7.

50 Figure 11 is a fragmentary vertical transverse section taken on line 11—11 Fig. 10.

Figure 12 is a horizontal section taken on line 12—12 Fig. 10.

55 Figure 13 is a fragmentary vertical transverse section taken on line 13—13 Fig. 2.

Figure 14 is a fragmentary vertical longitudinal section taken on line 14—14 Fig. 13.

Figures 15 and 16 are views similar to 60 Fig. 14 but showing different positions of the parts.

Figure 17 is a fragmentary sectional view showing the body or drum and one head of the barrel mounted on a chuck preparatory to seaming them together.

Figures 18 and 19 are similar views showing the successive operations of curling the co-operating flanges of the body and head by the turning roll, and then tightening or flattening the same by the finishing roll.

Figures 20 and 21 are perspective views 70 of the two parts of one of the trunnion nuts whereby each of the roll supporting slides is pivotally and adjustably connected with the companion rock arm whereby the same is actuated.

75 Similar characters of reference indicate like parts in the several figures of the drawings.

The barrel or cask which is to be operated upon in this seaming machine for the purpose of connecting the body or drum and the heads thereof consists in the present instance of a cylindrical body 30 of sheet metal and two disk-shaped heads 31 also of sheet metal secured to opposite ends of the body. 80 The latter is provided at its opposite ends with integral laterally projecting circumferential flanges 32 and each of the heads is provided at its edge with an annular flange 33 formed integral therewith.

90 In the operation of seaming the body and heads of a barrel each head is placed on a supporting ring 34 of a rotary chuck and the body is engaged on the inner side at each of its ends with the outer side of one 95 of the heads, as shown in Fig. 17. After the body and heads have been assembled and they are rotating about the axis of the barrel, the opposite ends of the latter are presented to two preliminary seaming rollers 35, each of which is adapted to rotate in engagement with the flanges of the body and head of one end of the barrel and produce a curl or partial interlock in the same,

as shown in Fig. 18.

100 Thereafter, and while the barrel is rotating with the chuck, the partly seamed flanges and heads at each end of the barrel are engaged by a finishing seaming roll 36 which rotates in engagement with these 105

110

flanges and operates to press the same into a flat condition and cause them to engage firmly with each other and finish the interlocking of the same, as shown in Fig. 19.

5 The main frame of the machine comprises a horizontal base 37 and two standards 38, 39 mounted on the front and rear ends of the base. The front standard 38 is preferably fixed on the base while the rear standard 39 slides at its lower end on a guideway or track 40 upon which the same is movable lengthwise of the machine to permit of adapting the same in the manufacture of barrels of different lengths. The numerals 41 and 42 represent front and rear chuck shafts or spindles which are arranged horizontally and lengthwise in line with each other, the front shaft 41 being journaled in a bearing in the lower part 10 of the front standard and the rear chuck shaft 42 being journaled in a bearing in the lower part of the rear standard. Each of these chuck shafts is provided at its inner end with a chuck having the form of a disk 25 43 upon which one of the supporting rings 34 is removably mounted so as to permit rings of different sizes to be employed for making barrels of different diameters.

30 The numeral 44 represents the main driving shaft of the machine which is journaled horizontally and lengthwise in bearings on the base and provided with front and rear driving pinions 45, 46, the front pinion 45 being secured to this shaft while the rear pinion 46 is splined on this shaft so as to permit the same to move lengthwise thereon, but compel the same to turn therewith. The driving shaft may be operated by the power of a prime mover of any suitable 35 character which latter is connected with this shaft in any approved manner.

40 The transmission mechanism which is interposed between this prime mover and the driving shaft 44 includes a clutch not shown 45 in the drawings, which clutch is controlled by means of a hand lever 29 connected with this clutch by means of a shipper rod 28, so that the movement of the driving shaft and the machine as a whole may be started 50 or stopped at will.

55 The front chuck shaft and the parts associated therewith are held against longitudinal movement but the rear chuck shaft is mounted on the rear standard so as to be capable of turning therein but held against longitudinal movement for the purpose of permitting the rear chuck mounted thereon to be moved toward and from the front chuck in order to grip the barrel between the 60 chucks for performing the seaming operations thereon and then releasing the barrel after the seaming operations have been completed.

65 Motion is transmitted from the driving shaft to the driven shaft 41 of the front

70 chuck by means of an intermediate shaft 47 journaled horizontally and lengthwise on the front standard and provided with an intermediate gear wheel 48 which meshes with its underside with the front driving gear pinion 45 while its upper side meshes with a driven gear wheel 27 on the front chuck shaft 41. Motion is transmitted from the driving shaft to the rear chuck shaft 42 by means of an intermediate shaft 49 journaled 75 horizontally and lengthwise on the rear standard and provided with an intermediate gear wheel 50 which meshes on its underside with the rear driving pinion 46 and on its upper side with a driven gear wheel 51 secured to the rear chuck shaft 42. As the rear standard 39 is moved lengthwise of the machine for the purpose of engaging the barrel to be operated upon and releasing the same after it is finished, the driving gear pinion 46 is compelled to move forwardly and backwardly with the rear standard by means of two brackets 52 arranged on the lower part of the rear standard and provided with bearings 53 which are arranged 80 on opposite sides of the rear driving gear wheel 46 and support the adjacent parts of the driving shaft, as shown in Fig. 4.

85 The advancing and retracting motion of the rear standard and the parts mounted thereon are preferably accomplished by the following means:—

90 The numeral 54 represents a crank shaft which is journaled horizontally and transversely in an extension 55 on the front end of the frame which extension preferably has the form of a house. On opposite ends of this crank shaft the same is provided with two disks 56, 57 preferably arranged on opposite sides of the extension 55 and each of these disks being provided with a crank 58. Extending lengthwise through the base of the machine and arranged along opposite sides of the driving shaft 44 mounted centrally therein, are two shifting rods 59 each 95 of which is connected at its front end with the crank on one of the disks 56, 57 while its rear end is connected with the rear standard so that upon rocking the shaft 54 the rear standard will be moved forwardly and 100 backwardly for the purpose of bringing the operating parts on the rear standard into engagement with the rear end of the barrel and disengaging the same therefrom. The connection between each of the shifting rods 105 is preferably so constructed that this rod can swing vertically relatively to this standard and the latter can also be adjusted on this rod for the purpose of adapting the machine to barrels varying in length. In the 110 preferred form this pivotal and adjustable connection between each shifting rod and the rear standard is constructed as follows:—

115 The numeral 60 represents a pivot block having an opening in its lower part through 120

which the rear screw thread end 61 of one of the shifting rods passes while the upper part of this block is pivoted on the adjacent part of the rear standard by means of a transverse pivot pin 62. On opposite sides of the pivot block 60 the shifting rod 61 is provided with adjusting screw nuts 63 which upon being turned in one direction or another will cause the rear standard to be 10 adjusted lengthwise forwardly or backwardly on the base in order to adapt the same to a particular length of barrel which is being operated upon, these adjusting screw nuts being held in place after adjustment by 15 means of clamping bolts 64, as best shown in Fig. 4.

The rocking motion of the crank shaft 54 is so determined that it turns back and forth through an arc of 180° and this rocking motion terminates on horizontally opposite sides 20 of the axis of this shaft so that when this shaft is turned forwardly the cranks 58 will be in their extreme relation to the crank shaft and horizontally in line therewith, as shown in Figs. 1 and 4, at which time the rear standard is moved forwardly so that the working parts thereon are in operative 25 relation to the rear end of the barrel. During the backward rocking stroke of the rock shaft 54 the cranks 58 are moved into their rearmost position relative to the crank shaft which is diametrically opposite to the foremost position of the same, whereby the rear standard is moved rearwardly through the 30 medium of the shifting rods 59, thereby releasing the barrel which has been operated upon and permitting a new unseamed barrel to take its place. This alternate rocking of the shaft 54 is effected by motion derived 35 from the main shaft 44, which motion is transmitted by a mechanism which includes clutches and a reversing gearing whereby the connection between the driving shaft and the crank shaft 54 may be coupled and uncoupled 40 and the direction of rotation of the crank shaft relative to the driving shaft may be reversed so that the crank shaft turns alternately in opposite directions.

Although this transmitting mechanism 45 may be varied in its details, the same may be preferably constructed as follows:—

The numeral 65 represents an upright clutch shaft journaled in the frame extension 55 and provided at its lower end with 50 a worm 66 meshing with a worm wheel 67 on the crank shaft 54. On the outer or front end of the intermediate shaft 47 the same is provided with a central beveled gear wheel 68 which latter meshes on its lower 55 side with a lower beveled gear wheel 69 and on its upper side with an upper beveled gear wheel 70, said lower and upper gear wheels 69 and 70 being mounted loosely on the clutch shaft 65 and rotated in opposite directions by an intermediate driving beveled 60 gear wheel 68 between the same. Between the upper and lower gear wheels 69 and 70 two clutches 71 and 72 are mounted on the clutch shaft 65, the lower clutch 71 being adapted to connect and disconnect this 70 clutch shaft with the lower beveled gear wheel 69, and the upper clutch 70 being adapted to connect and disconnect the upper beveled gear wheel 70 with this clutch shaft. The two clutches 71 and 72 are operated in 75 unison from a horizontal controlling shaft 73 which is journaled horizontally and transversely in the adjacent part of the extension 55 and provided with an inwardly projecting fork 74 which engages with the movable 80 members of both clutches 71 and 72. At its front end this clutch controlling shaft 73 is provided with a hand lever 75 whereby the clutch controlling shaft 73 may be turned manually for coupling either of the clutches 85 71 or 72. In the position of the parts shown in Fig. 4 the clutch rock arm 74 is in its central position so that both clutches 71 and 72 are uncoupled and no motion is transmitted from the intermediate shaft 47 to the 90 clutch shaft 65 at which time the crank shaft 54 is at rest at either extreme of its rocking motion and the rear standard is at rest either in its forward or rearward position.

Upon coupling the lower clutch 71 the crank shaft 54 is turned in the direction for moving the rear standard forwardly and upon coupling the upper clutch 72 the crank shaft 54 is turned in the direction for moving the rear standard backwardly.

The shifting of the clutches 71 and 72 out of their neutral position for the purpose of causing the crank shaft to turn in one direction or the other for causing the longitudinal movement of the rear standard to begin 105 is preferably effected manually but the stopping of the rocking motion of the crank shaft at either extremes of its stroke is preferably effected automatically and thereby not only relieves the attendant from this 110 work but also assures stopping of the longitudinal movement of the rear standard at the end of its forward and backward strokes without depending on the attendant.

The preferred means for accomplishing 115 this purpose consists in providing one of the crank disks 56 on its periphery with two tappets or shoulders 76, 77 which are arranged on diametrically opposite sides of the disk 56 and face circumferentially in 120 opposite directions and are adapted to engage alternately with opposite sides of a tappet or throw-out lever 78 arranged on the adjacent part of the clutch controlling lever 73. It follows from this construction 125 that if the clutch controlling shaft 73 has been turned manually in the direction for coupling the upper clutch 72 for causing the crank shaft 54 to turn in the direction for moving the rear standard backwardly, as

shown in Fig. 5, that during the last part of this movement the rear tappet or shoulders 76 of the respective crank disc 56 will engage the lower end of the tappet or throw-out arm 78, as shown in Fig. 5, and when the crank shaft 54 has completed its movement so that the cranks 54 are horizontally in line therewith then the clutch controlling shaft 73 will be turned into a position in 10 which the shifting arm 74 is arranged in a horizontal or neutral position as shown by full lines in Fig. 4 and the upper clutch 72 will be disengaged so as to arrest the rotation of the crank shaft 54 the instant that the rear standard 59 reaches its rearmost position.

After the rock shaft 73 has been turned in the direction for coupling the lower clutch 71 the throw-out or restoring arm 78 will be 20 turned manually in the opposite direction from its central position and as the cranks 58 move from the rear side of the crank shaft 54 to the front side of the same the front restoring shoulder or tappet 77 on the respective crank disk 56 will engage with the opposite side of the restoring arm 78 and move the same from its operative position back to its central or neutral position and thereby uncouple the clutch 71 so that 30 the crank shaft will be arrested in its rotation when the cranks 58 are in their foremost position, as shown in Figs. 1 and 4, and the rear standard has been moved forwardly into its operative position.

35 Adjacent to the inner side of the upper part of each standard is arranged one of the preliminary seaming rolls 35 and one of the finishing rolls 38, these rolls being arranged above the adjacent chuck and in 40 spaced relation circumferentially so that the seam of these rolls may engage independently of each other with the flanges of the body or drum and head on the corresponding end of the barrel for producing the successive curling and finishing operations on 45 the seamed joint at the respective end of the barrel.

Each of these rolls is so mounted and operated that the same is moved periodically toward and from the flanges on the respective ends of the barrel members and the same is also capable of bodily adjustment radially on the axis of the barrel for adapting this roll to the flanges on the corresponding end thereof in order to permit of seaming barrels of different diameters and also to facilitate setting up the machine and taking up wear. The particular embodiment of this mechanism is constructed as follows:

60 The numeral 79 represents a cam shaft arranged horizontally and lengthwise of the machine and journaled in bearings 80 and 81 arranged at the upper ends of the stationary front standard and the longitudinal movable rear standard, said shaft be-

ing mounted in such manner that the same is only capable of turning in the front standard but incapable of sliding lengthwise therein, but it is capable of both turning and sliding in the bearing of the rear standard.

This shaft is rotated once for each cycle of operations of the machine and preferably derives its motion from the main shaft by means of a transmitting mechanism which may be of any suitable construction, but in the present case this transmitting mechanism preferably consists of a horizontal longitudinal clutch shaft 82 journaled in suitable bearings on the front standard and provided with a gear wheel 83 which meshes with a gear pinion 84 on the front chuck shaft 41, an intermediate shaft 85 journaled horizontally and lengthwise on the front standard and provided with a gear wheel 86 which meshes with a gear pinion 87 on the clutch shaft 82 and also provided with a gear pinion 88 which meshes with a gear wheel 89 on the front end of the cam shaft 79, and a clutch 90 adapted to connect and disconnect the clutch shaft 82 and the gear wheel 83. This clutch is operated by means of a rock arm 91 which is secured to a rock shaft 92 journaled horizontally and transversely on the front standard and provided at its front end with a handle 93 so that this clutch can be operated manually.

The seaming rolls 35 and 38 are pivotally mounted on the lower ends of two carriages 94, 95 which are movable toward and from the periphery of the barrel for engaging and disengaging these rolls with the respective flanges of the body and head. In the preferred construction these carriages are guided in their movement by slidingly engaging the opposing inner lateral sides of the carriages with each other, while the backs or rear sides of the same engage with the back plate 96 over a guideway, the outer lateral sides of these carriages engage with side walls 97 of this guideway, and gibs or rails 98 are secured by bolts 99 with the edges of the walls 97 and engage with the inner sides of the carriages 94 and 95 adjacent to the outer corners thereof, as best shown in Figs. 7, 8, and 12. By this means the two carriages 94 and 95 are guided with their opposing surfaces upon each other and are also guided on the guideway 96 and 97, which latter effect forms a guide yoke.

This last mentioned yoke is preferably also guided on the adjacent standard so that the guideway for each carriage may be moved toward and from the axis of the chucks to permit of adapting this guide for most effectively controlling the movement of the roll carriages when operating upon barrels of different diameters. For this purpose each guide yoke is provided on its outer side with laterally projecting guide

flanges 100, each of which is received in a vertical guideway formed by a rabbet 101 on the adjacent part of the standard and a gib 102 secured to this standard by means 5 of bolts 103, as best shown in Figs. 7, 8 and 12. Vertical motion may be imparted to the guide yoke for adjusting the position of the same by any suitable means but preferably by means of an upright adjusting screw 104 working in a threaded opening 105 in the upper part of the guide yoke, and having a 10 wrist 106 which turns in a bearing 107 on the upper part of the respective standard, collars 108 secured to this screw and engaging 15 the upper and lower sides of the bearing 107, and a square 109 formed on the upper end of the screw 104 and adapted to receive a wrench or other tool for turning this screw whenever it is desired to raise 20 and lower the guide yoke.

Mounted upon the cam shaft 79 are two pairs of rotary cams 110, 111, the members of each pair being arranged adjacent to the inner side of one of the standards and the 25 member 110 of each pair being adapted to shift the respective preliminary curling roll inwardly, its companion cam 111 being adapted to move the corresponding finishing roll inwardly into its operative position. 30 The cams 110, 111 which operate the rolls mounted on the stationary standard are secured to the cam shaft 79, but the cams 110, 111 which operate the preliminary curling and finishing rolls associated with the movable standard 39 are mounted on the rear 35 movable standard so that these last mentioned rolls are compelled to turn with the cam shaft 79 but are capable of sliding lengthwise thereon in unison with the rear standard, this being preferably accomplished 40 by means of a spline in any suitable and approved manner.

On their inner sides the cams 110, 111 of each pair engage with rollers 112, 113 which are mounted on vertically swinging rock arms 114, 115 which have their free inner ends arranged side by side while their outer ends are pivoted to the upper part of the respective standard by means of horizontal 50 longitudinal pivots 116, 117. Each of the rock arms 114, 115 is connected with its respective roll carriage in such manner that the vertical movement of each of these rock arms causes the respective carriage to rise 55 and fall and these connecting means are so constructed that the position of each of these roll carriages can be adjusted relatively to the companion rock arm for adapting the respective roll to barrels of different diameters.

In the preferred construction shown in the drawings this is accomplished by means of a shifting rod 118 having the form of a screw which works with its threaded body, 60 a screw threaded opening 119 formed in a

trunnion 124 which is pivotally mounted on the upper part of the respective roll carriage, while the upper end of this screw shifting rod is provided with a head 120 the upper side of which engages with the 70 underside of the swivel head 121 and the under side of which is engaged with a coupling sleeve 122 having a shoulder which engages with the underside of the head 120, and a screw thread whereby this coupling is 75 connected with the swivel head 121, as best shown in Fig. 10. Each of the swivel heads is pivotally connected at its central part by means of a horizontal longitudinal pin 123 with the companion rock arm 114 or 115. 80

As the salient part of the cam 110 or 111 engages the roller of its corresponding rock arm and depresses the same the corresponding carriage is moved downwardly. During this time the swivel head 121 is free to turn 85 on the pivot pin 123 and the trunnion 124 turns at its opposite ends in bearings 125 in the upper end of the respective roll carriage. In order to prevent the screw connecting rod 118 from becoming loose and turning while 90 the machine is in operation, the trunnion nut 124 is preferably divided into sections which are clamped against opposite sides of this screw connecting rod. As shown in Figs. 10, 20 and 21 this trunnion nut is divided along a line, one half of its length extending from one end thereof to the center of the threaded opening thereof, and also radially from the axis of this trunnion nut to the periphery thereof in line with the 100 center of the screw threaded opening therein, thereby forming two sections one of which 126 represents three-quarters of the trunnion nut and the other, 127, one-quarter of the same, as shown in Figs. 20, 21. 105

When these sections are assembled they form a complete nut the opposite ends of which are cylindrical and form trunnions which turn in the bearings 125. These sections are clamped against opposite sides of the screw connecting rod 118 by means of screws 128 which connect these trunnion sections, thereby preventing the screw connecting rod 118 from turning while it is in operation.

The rising movement of the roll carriages is effected by spring pressure and is preferably accomplished by means of a shifting rod 129 pivotally connected at its lower end with the upper end of one of the swivel 120 heads 121 and passing with its central part through a guide pocket 130 on the adjacent upper part of the respective standard, and a lifting spring 131 bearing at its lower end against the bottom of the pocket 130 and at 125 its upper end against a screw nut 132 at the upper end of the shifting rod 129, as best shown in Fig. 10.

In the operation of the machine the cam 110 first depresses its companion cam arm 130

114 so as to engage its roll with the flanges at the corresponding end of the barrel and seaming them together, as shown in Fig. 7, after which this roll and associated parts 5 are raised by the respective spring lifting mechanism, and then the cam 111 causes the finishing roll to be depressed in engagement with the flanges on the respective end of the barrel for seaming them together, as 10 shown in Fig. 8, and thereafter this last mentioned roll is also lifted by its spring mechanism into an inoperative position so that the completed barrel is free to be removed.

15 Means are provided whereby the clutch 90 is automatically opened for disconnecting the seaming roll shifting mechanism from the continuously rotating driving shaft at the end of each cycle of seaming 20 operations, and after the seaming rolls have been withdrawn from the barrel, thereby relieving the operator from this work and insuring withdrawal of the seaming rolls from the barrel into the proper position at 25 all times.

The preferred means for this purpose which are shown in Figs. 1, 2, 3, 4, 6, 13, 14, 15 and 16 are constructed as follows:—

The numeral 133 represents the trip, re- 30 turn or throw-out arm secured to the shaft 92 by which the clutch 90 is opened and closed. Below the throw-out arm 133 is arranged a vertically movable slide 134 which is guided on the adjacent part of the 35 front standard by means of pins 135 secured to this standard fastened through a vertical slot 136 on this slide, as shown in Figs. 13 to 16. On one side of this slide is mounted a latch 137 which is capable of a vertically 40 sliding movement on the slide 134 and also a pivotal movement thereon in a direction toward and from the throw-out arm 133, this combined sliding and pivotal connection being effected by means of a pin 138 45 mounted on the slide 134 and passing through a vertical slot 139 on the latch 137. This latch is yieldingly held in an elevated position on this slide 134 by means of a spring 140 interposed between the lower end 50 of this latch and the shoulder 141 on the lower part of this slide. This latch is also yieldingly turned in the direction for engaging its upper end with the free end of the throw-out arm 133 by means of a spring 55 142 interposed between the lower end of the slide 134 and the lower arm of the latch 137. Near its upper end the latch is provided on that side facing the free end of the throw-out arm with a rabbet forming an upwardly facing shoulder 143 which is adapted to engage with the free end of the throw-out arm, and at its extreme upper end the latch is provided with a throw-off incline 144 which is adapted to engage with a normally fixed but preferably adjustable throw-

off abutment 145 which preferably consists of a screw arranged in a bracket 146 on the adjacent part of the main frame.

When the clutch 90 is in its open position, as is shown by dotted lines at the left of Fig. 14 and by full lines in Fig. 4, the throw-out arm 133 is elevated into a horizontal position, the slide 134 is raised into its highest position, and the latch 137 is also raised into its highest position on the slide and has its upper end moved laterally by the wedge action between the incline 144 and the abutment 145, so that the shoulder 143 of this latch is out of engagement from the throw-out arm 133, as shown in Fig. 14. 70 The slide 134 is normally held in its depressed position together with the parts mounted thereon by gravity and its upward motion is effected by means of a vertically swinging rock lever 147 pivoted on the upper part of the front standard of the main frame and provided at one end with a roller 148 engaging with a cam 149 on the cam shaft 79, while its opposite arm is connected by a shifting rod 150 with the upper part 75 of the slide 134, as shown in Figs. 1, 2, 3, 4, 80 and 6.

As the operator now manually turns the rock shaft 92 by means of a hand lever 93 so as to close the clutch 90 and couple the 95 driving mechanism with the seaming roll shifting mechanism, the clutch arm 91 moves from the position shown by full lines in Fig. 4 to the position shown by dotted lines in the same figure, which last mentioned position corresponds to the position of this clutch arm indicated by dotted lines at the right of Fig. 14. As the operator turns the clutch operating shaft 92 in the direction for closing this clutch the throw-out arm is shifted from the horizontal position shown by full lines in Fig. 14 to the 100 downwardly inclined position shown by dotted lines in the same figure.

When the machine comes to rest after the 110 seaming rolls perform their operations on the barrel, the high or salient part of the cam 149 is in engagement with the roll 148 of the rock arm as shown in Fig. 3, and has thereby raised the slide 134 into the position shown in Figs. 2 and 14. During the initial part of the rotary movement of the cam shaft 79 after the clutch 90 has been closed the salient part of the cam 149 is moved out of engagement from the roller 120 148 of the rock lever 147 and thereby permits this roller and the corresponding arm on this lever to be raised while the opposite arm is depressed, as shown by dotted lines in Fig. 3, and also permits the slide 134 to 125 descend by gravity into its lowest position indicated in Fig. 15. During such descent of this slide the latch 137 is also lowered and the incline 144 at its upper end is permitted to ride along the stationary abutment 145 130

so that the upper end of this latch will be moved by the action of the spring 142 toward the throw-out arm 133, and the upwardly facing shoulder 143 of the latch is 5 moved underneath the throw-out arm 133, as shown in Fig. 15.

This automatic throw-off mechanism will now remain in this last mentioned position until the cam shaft 79 has nearly completed 10 one complete rotation and during the last part of this rotation the salient part of the cam 149 engages with the roller 148 and depresses the corresponding arm of the rock lever 147 and raises the opposite arm thereof, 15 as shown by full lines in Fig. 3, whereby the slide 134 is raised.

During the first part of this raising movement of the slide the shoulder 143 of the latch bears against the underside of the 20 throw-out arm 133 and tends to raise the same but the resistance of the clutch 90 causes the slide 134 to effect the first part of this movement independently of the latch and during 25 this time the spring 140 is compressed until the pin 138 on the slide releases the upper end of the slot 139 on the latch, as shown in Fig. 16. Thereafter the latch moves upwardly in unison with the slide 134 and causes the throw-out arm 133 to be moved 30 from the downwardly inclined position shown in Fig. 15 to the horizontal upper position shown in Fig. 16 whereby the clutch 90 is uncoupled during the last part of the upward movement of the slide 134. At the 35 same instant that the clutch 90 is uncoupled the latch has been shifted laterally away from the throw-out arm 133 by the wedge action of the incline 144 against the abutment 145 so that the shoulder 143 of the 40 latch is completely disengaged from the throw-out arm 133, and when this disengagement occurs the spring 140 immediately completes the upward movement of the latch and causes the incline 143 to complete 45 the lateral movement of the latch away from the free end of the throw-out arm 133, as shown by full lines in Fig. 14, in which last mentioned position the latch fully clears the throw-out arm 133 and permits the latter to 50 be subsequently turned downwardly manually by the operator for again closing the clutch 90 independently of the automatic throw-out mechanism.

The means for supporting the barrels and 55 lifting them into a position for engagement with the chucks and again supporting the same preparatory to removal from the machine are preferably constructed as follows:—

Between the upper side of the base of the main frame and the lower side of the chucks is arranged a vertically movable platform 60 which is preferably of skeleton form and comprises two transverse bars or arms 151 pivoted by means of hinges 152 or the like

to the rear end of the base so that these bars can swing vertically, and two centering blocks 153 arranged on the upper side of each of the arms 151 and on opposite sides of the driving shaft 44, a rock shaft 155 70 arranged horizontally and lengthwise within the base and journaled in suitable bearings thereon, lifting arms 158 secured to this rock shaft and projecting inwardly therefrom, a link 157 connecting the inner 75 end of each lifting arm 158 with the lower side of one of the elevating arms 151, and a treadle 154 secured to the rock shaft 155 and projecting forwardly through an opening in the base and provided at its front end 80 with a pedal 156, as best shown in Fig. 7. Due to this construction the rock arms 158, the treadle 154 and the rock shaft connecting the same, in effect form a foot lever which is operatively connected by the link- 85 age formed by the links 157 and constitute the means whereby the barrel elevating platform may be raised and lowered.

This platform is arranged in its lowermost position and rests upon the upper side 90 of the base when the members of the barrel to be seamed together are placed in the machine. After the barrel has been thus placed upon the elevating platform it engages with the centering blocks 153 which 95 form a saddle or seat whereby this barrel is prevented from rolling toward either side of the machine, and while thus supported the operator depresses the pedal 156 thereby rocking the foot lever in the direction for 100 raising the elevating platform and causing the barrel to be centered relatively to the chucks so that upon subsequently moving the rear standard toward the front standard the heads at the opposite ends of the barrel 105 will be properly gripped by the chucks and centered for subsequent operations thereon by the seaming rolls. After the seaming operation has been completed the operator raises the platform so as to engage the underside of the barrel and cause the latter to be directed from the machine toward the rear side of the same, leaving the space clear for the reception of another barrel which is introduced into the machine from the front 110 side thereof. 115

I claim as my invention:—

1. A machine for seaming together the heads and bodies of sheet metal barrels comprising a frame having a base, a fixed standard, a movable standard slidable on said base toward and from the fixed standard, chucks rotatably mounted on said standards and adapted to receive a barrel between them, and means for reciprocating said movable 125 standard including a crank rotatably mounted on said base, a shifting rod connected at one end with said crank and at its opposite end with said movable standard, a worm wheel connected with said crank, a 130

- worm meshing with said worm wheel, a clutch shaft carrying said worm, a driving gear wheel turning constantly in the same direction, driven gear wheels mounted concentrically with the clutch shaft and meshing with diametrically opposite sides of the driving gear wheel, and clutches for connecting either of said driven gear wheels with said clutch shaft.
- 10 2. A machine for seaming together the heads and bodies of sheet metal barrels comprising a frame having a base, a fixed standard, a movable standard slidable on said base toward and from the fixed standard, chucks rotatably mounted on said standards and adapted to receive a barrel between them, and means for reciprocating said movable standard including a crank rotatably mounted on said base, a shifting rod connected at one end with said crank, and at its opposite end with said movable standard, a worm wheel connected with said crank, a worm meshing with said worm wheel, a clutch shaft carrying said worm, a driving gear wheel turning constantly in the same direction, driven gear wheels mounted concentrically with the clutch shaft and meshing with diametrically opposite sides of the driving gear wheel, clutches for connecting either of said driven gear wheels with said clutch shaft and means for actuating said clutches comprising a tappet disk provided on diametrically opposite sides with tappet faces, a rock shaft carrying said worm wheel, a crank and disk, and means for transmitting motion from said tappet disk to said clutches.
3. A machine for seaming together the heads and bodies of sheet metal barrels comprising a frame having a base, a fixed standard, a movable standard slidable on said base toward and from the fixed standard, chucks rotatably mounted on said standards and adapted to receive a barrel between them, and means for reciprocating said movable standard including a crank rotatably mounted on said base, a shifting rod connected at one end with said crank and at its opposite end with said movable standard, a worm wheel connected with said crank, a worm meshing with said worm wheel, a clutch shaft carrying said worm, a driving gear wheel turning constantly in the same direction, driven gear wheels mounted concentrically with the clutch shaft and meshing with diametrically opposite sides of the driving gear wheel, clutches for connecting either of said driven gear wheels with said clutch shaft and means for actuating said clutches comprising a tappet disk provided on diametrically opposite sides with tappet faces, a rock shaft carrying said worm wheel, a crank and disk, a reversing shaft, a tappet arm mounted on said reversing shaft and adapted to be engaged by said tappet faces
- and turned alternately in opposite directions, a clutch arm arranged on said reversing shaft and engaging with said clutches, and a hand lever connected with said reversing shaft.
4. A machine for seaming together the heads and bodies of sheet metal barrels comprising means for rotatably supporting the barrel, a seaming roll adapted to seam the barrel, and means for moving said roll toward and from said barrel including a carrier supporting said roll and movable laterally toward and from said barrel, a trunnion screw nut pivotally mounted on said carrier, a shifting screw engaging its threaded end with said trunnion screw nut, a vertically swinging rock arm, and a swivel having a rotatable connection with said screw and pivoted on said rock arm.
5. A machine for seaming together the heads and bodies of sheet metal barrels comprising means for rotatably supporting the barrel, a seaming roll adapted to seam the barrel, and means for moving said roll toward and from said barrel including a carrier supporting said roll and movable laterally toward and from said barrel, a trunnion screw nut pivotally mounted on said carrier, a shifting screw engaging its threaded end with said trunnion screw nut, a vertically swinging rock arm, a swivel having a rotatable connection with said screw and pivoted on said rock arm, a rotary cam engaging said arm for turning the same in one direction, and means for moving the arm and parts connected therewith in the opposite direction including a shifting rod connected with the swivel and having a screw nut, and a spring interposed between said screw nut and a support.
6. A machine for seaming together the heads and bodies of sheet metal barrels comprising means for rotatably supporting the barrel, a seaming roll adapted to seam the barrel, and means for moving said roll toward and from said barrel including a carrier supporting said roll and movable laterally toward and from said barrel, a trunnion screw nut pivotally mounted on said carrier, a shifting screw engaging its threaded end with said trunnion screw nut, and a vertically swinging rock arm connected with the other end of said shifting screw, said trunnion screw nut being divided in sections on a line extending through the threaded opening of the nut and said sections being connected by clamping screws whereby the sections are clamped against the shifting screw.
7. A machine for seaming together the heads and bodies of sheet metal barrels comprising means for rotatably supporting the barrel, a seaming roll adapted to seam the barrel, and means for moving said roll toward and from said barrel, including a car-

rier supporting said roll and movable laterally toward and from said barrel, a laterally movable yoke provided with a guideway for said carrier, a frame having a guideway 5 on which said yoke is adjustably mounted and means for adjusting said yoke on said frame consisting of an adjusting screw engaging a threaded opening on said yoke and mounted on said frame so as to be capable of turning but incapable of longitudinal 10 movement.

8. A machine for seaming together the heads and bodies of sheet metal barrels comprising means for rotatably supporting the 15 barrels, a pair of seaming rolls arranged side by side and adapted to engage the barrel for seaming the same, carriers supporting said rolls and having their inner opposing sides engaging each other, a yoke having a guideway 20 engaging the rear and outer sides of both carriers, gibs secured to the yoke and outer front edges of said carriers, and means for actuating said carriers for moving the rolls toward and from said barrel.

25 9. A machine for seaming together the heads and bodies of sheet metal barrels comprising means for rotatably supporting the barrel to be seamed, two seaming rolls movable alternately toward and from the barrel 30 for seaming the same, and means for actuating said rolls including carriers supporting said rolls, cams for shifting said carriers and a shaft carrying said cams.

35 10. A machine for seaming together the heads and bodies of sheet metal barrels comprising means for rotatably supporting the barrel to be seamed, two seaming rolls movable alternately toward and from the barrel 40 for seaming the same, and means for actuating said rolls including carriers supporting said rolls, guideways for said carriers, rock arms connected with said carriers, cams for shifting said rock arms, and a rotary shaft on which said cams are mounted.

45 11. A machine for seaming together the heads and bodies of sheet metal barrels comprising means for rotatably supporting the barrels, a driving shaft, a seaming roll for engaging the adjacent edges of a head and 50 body, means for moving said roll toward and from its operative position including a driven shaft which makes a turn for each cycle of seaming operations, manual means for connecting said driven shaft with said 55 driving shaft and beginning each cycle of seaming operations including a clutch, a clutch arm engaging said clutch, a rock shaft carrying said clutch arm, and a hand lever connected with said rock shaft, and auto-

matic means for uncoupling said driven 60 shaft from said driving shaft at the end of each cycle of seaming operations including a vertically movable slide, a rock lever having one arm connected with said slide, a cam turning with said driven shaft and engaging 65 with the other arm of said rock lever, a throw-out arm connected with said rock shaft, a latch capable of a transverse rocking and a longitudinal movement on said slide and having a trip shoulder adapted to 70 engage said throw-out arm and also having a throw-off incline, a spring for turning the latch transversely toward said throw-out arm for engaging the latter with said shoulder, a spring for moving said latch lengthwise on the slide toward said throw-out arm, and a normally stationary throw-off abutment adapted to be engaged by said incline for shifting the latch and disengaging its shoulder from said throw-out arm at the 75 last part of the longitudinal movement of 80 said slide under the action of said cam.

12. A machine for seaming together the heads and bodies of sheet metal barrels comprising means for rotatably supporting the 85 barrels, a driving shaft, a seaming roll for engaging the adjacent edges of a barrel head and barrel body, means for moving said roll toward and from its operative position including a driven shaft which makes a turn 90 for each cycle of seaming operations, manual means for connecting said driven shaft with said driving shaft and beginning each cycle of 95 seaming operations including a clutch, and a hand operated lever operatively connected with said clutch; and automatic means for uncoupling said driven shaft from said driving shaft and beginning each cycle of 100 seaming operations, including a slide, a cam turning with said driven shaft and operatively associated with said slide, a throw-out member operatively associated with said slide, a latch capable of a transverse and also a longitudinal movement relative to 105 said slide, means for moving said latch toward said throw-out member for interlocking the same therewith, means for moving said latch lengthwise of said slide toward said throw-out member, and a normally stationary throw-off abutment adapted to cooperate with said latch and disengage the latter 110 from said throw-out member during the last part of the longitudinal movement of said slide under the action of said cam.

In testimony whereof I hereby affix my 115 signature.

BROR J. LINDGREN.
